M. C. HUTCHINSON.
REVERSIBLE TAPER ROUGHING REAMER.
APPLICATION FILED AUG. 31, 1918.

1,348,115.

Patented July 27, 1920.

UNITED STATES PATENT OFFICE.

MORTON C. HUTCHINSON, OF WOODBURY, NEW JERSEY, ASSIGNOR OF ONE-HALF TO
LEON G. BUCKWALTER, OF MERCHANTVILLE, NEW JERSEY.

REVERSIBLE-TAPER ROUGHING-REAMER.

1,348,115.

Specification of Letters Patent. Patented July 27, 1920.

Application filed August 31, 1918. Serial No. 252,136.

To all whom it may concern:

Be it known that I, MORTON C. HUTCHINSON, a citizen of the United States, residing at Woodbury, in the county of Gloucester, 5 State of New Jersey, have invented a new and useful Reversible-Taper Roughing-Reamer, of which the following is a specification.

It is frequently desirable in different 10 classes of shipyard and machine shop work to employ at one time a reamer having a taper converging toward the driving machine or motor, and at other times to have the taper of the reamer converge away therefrom, all of which advantages are readily 15 attained in my invention, which embodies a bar slotted in a novel manner in conjunction with a novel construction and collocation of cutters which are capable of being reversed or interchanged, whereby I have produced 20 in a single concrete unitary structure a reversible reamer by merely changing or reversing the position of the cutters in the bar holding them.

25 To the above ends my invention consists of a novel construction of a reversible taper roughing reamer, the object of which is to provide a tool capable of reaming the walls of a parallel or straight hole preferably in 30 a piece of metal to a taper, thereby causing the hole to take the form of a frustum of a cone, the tool being provided with a novel construction and collocation of slots and reversible cutters, whereby by reversing said 35 cutters I am enabled to ream a taper converging either in one direction or in a direction exactly opposite, while the position of the driving machine or motor remains the same.

40 My invention further consists of a novel construction enabling the several cutters to be readily and accurately inserted and centered in the bar, so that their cutting edges shall always remain symmetrical with the 45 axis of the bar.

It further consists of a novel construction of reversible cutters employed.

For the purpose of illustrating my invention, I have shown in the accompanying 50 drawing one form thereof which is at present preferred by me, since the same will be found in practice to give satisfactory and reliable results, although it is to be understood that the various instrumentalities of 55 which my invention consists can be vari-

ously arranged and organized and that my invention is not limited to the precise arrangement and organization of these instrumentalities as herein shown and described.

Figure 1 represents a perspective view of 60 a reversible taper roughing reamer embodying my invention.

Fig. 2 represents a side elevation of Fig. 1.

Fig. 3 represents a side elevation of my 65 novel reamer having cutters similar to that seen in Fig. 2, but having said cutters reversed, so that the taper of the reamer and of the reamed hole will converge toward the driving machine or motor.

Fig. 4 represents an end view of Fig. 2. 70

Fig. 5 represents a side elevation of either of the two end cutters seen in Figs. 1 and 2.

Fig. 6 represents a side elevation of the intermediate cutters seen in Figs. 1 and 2.

Fig. 7 represents a side elevation of the 75 bar or body of the reamer with the cutters removed therefrom.

Similar numerals of reference indicate corresponding parts in the figures.

Referring to the drawings:— 80

1 designates my novel construction of reamer, the same comprising a straight or tapered cylindrical bar, rod, mandrel or the like, 2, one end of which terminates in a taper shank 3 of the conventional type, 85 which is adapted to be inserted in the chuck or tool holder of any of the conventional forms of driving machines, such as a rotary pneumatic or electric drilling engine (not shown).

89 In the present embodiment of my invention I locate in the bar 2, the alining slots 4, 5, and 6, which pass diametrically through the axis of the bar 2, and are in the present instance three in number. The slot 7 95 passes diametrically through the bar 2 at a point intermediately of and at a right angle to the slots 4 and 5, while the alining slot 8 passes diametrically through the bar 2 at a point intermediate of and at a right 100 angle to the slots 5 and 6.

In the present instance, I have shown the alining slots 4, 5, and 6 as being three in number, and the intermediate alining slots 7 and 8 as being two in number, but it will 105 be apparent that the relative number of said slots may be increased or diminished, according to requirements.

9 designates the cutter inserted in the slot 4, 10 the cutter inserted in the slot 5, 110

11 the cutter inserted in the slot 6, and 12 and 13 designate the cutters inserted respectively in the slots 7 and 8, the two latter cutters, when in assembled position, 5 extending at a right angle to the cutters 9, 10 and 11 when the latter are assembled, as is evident.

Each of the cutters 9, 12, 10, 13 and 11 in the order named are of decreasing length 10 and are provided with outer inclined terminal walls or cutting edges, which converge toward the outer end 14 of the reamer, when the cutters are assembled, as seen in Figs. 1 and 2. The two end cutters as 9 15 and 11 have opposite shallow rectangular, central notches or recesses as 15, cut in each side at a point where the axis of the bar intersects the plane of the cutter, as will be understood from Fig. 5, while the intermediate cutters 12, 10 and 13 are similar 20 to the cutter seen in Fig. 6, but of varying lengths, as explained, and have a single, central, rectangular notch or recess 16 therein, the dimensions of said notch 16 being 25 such as to permit the thickness of another contiguous cutter to slip into it, whereby one cutter locks into its adjacent cutter, thereby causing the series of cutters when assembled to become automatically centered 30 and to remain symmetrically placed with respect to the axis of the bar 2.

It will be obvious that each slot in the bar 2 is made wider than the cutter by the depth of the notch 16 in the cutter, as will 35 be understood from Fig. 7, to permit of inserting each cutter in its slot.

The set screw 17 screwed into the end 14 of the bar 2 has its inner terminal engaging the recess 15 of the cutter 11 when the 40 construction seen in Figs. 1 and 2 is employed, and the cutter 9 when the construction seen in Fig. 3 is employed, for the purpose of keeping the cutters locked into the notches of the adjacent cutters, 45 thus effectively securing all the cutters firmly in their proper positions.

18 designates a dummy key inserted in the slot 19, the latter being located on one side of the slot 4 farthest from the end 50 14 of the bar 2, as best seen in Fig. 7, which dummy key maintains the last cutter 9 in its position with respect to the axis of the bar, it being apparent that each cutter except the last one as 9, in Figs. 1 and 12, 55 and 11 in Fig. 3 is locked in position by the next adjacent one, hence it is desirable to provide the dummy key 18 to secure the last cutter 9 or 11 as the case may be.

The object of providing the large cutter 60 9 and the small cutter 11 with the notches 15 on both sides is to permit said cutters 9 and 11 to be reversed, when desired from the positions seen in Figs. 1 and 2, to the position seen in Fig. 3, as will be explained.

65 It will be apparent that since the cutting

edge of one cutter overlaps that of its adjacent cutter, as seen in Figs. 1 or 4, there is no liability of circumferential ridges being formed, where the cut of one cutter ends and that of the next begins, 70 thus a smooth straight wall is provided in the taper reamed hole.

It will be apparent to those skilled in the art, that when the cutters are assembled as seen in Figs. 1 and 2, a very efficient tool is 75 provided capable of reaming the walls of a parallel or straight hole to a taper, and causing the hole when reamed to take the form of a frustum of a cone, the taper of the reamed hole when the cutters are assembled, 80 as seen in Figs. 1 and 2, converging away from the driving machine or motor as is evident. When it is desired to have the taper of the reamed hole converge toward the driving machine or motor, it is only necessary to loosen the set screw 17 and collocate the cutters as seen in Fig. 3, the large cutter 9 being inserted in the slot 6, and the small cutter 11 in the slot 4, and the intermediate cutters being also reversed so as to appear 85 as seen in Fig. 3, whereby the taper of the reamed hole will converge toward the driving machine or motor. Hence by my invention the taper of the reamed hole can converge either in one direction, or in a direction 90 exactly opposite, while the position of the driving engine or motor remains the same. This feature of a reversible reamer being formed in a single unitary structure is a very desirable feature in certain classes 95 of shipyard or machine shop practice, and is readily accomplished in my device by merely changing the position of the cutters in the bar holding them, as heretofore explained.

I have thus in a single structure provided a reversible reamer, wherein the cutters can be inserted in position or interchanged or reversed in a very short space of time, and in case of injury to any of the cutters, it 100 can be readily sharpened or replaced by a new one, as is evident, and by my device a single reamer structure can readily do the work which has heretofore necessitated the employment of two reamers having reverse 105 tapers.

It will now be apparent that I have devised a novel and useful construction of a reversible taper roughing reamer which embodies the features of advantage enumerated 110 as desirable in the statement of the invention and the above description, and while I have, in the present instance, shown and described a preferred embodiment thereof which will be found in practice to give satisfactory and 115 reliable results, it is to be understood that the same is susceptible of modification in various particulars without departing from the spirit or scope of the invention or sacrificing any of its advantages.

Having thus described my invention what I claim as new and desire to secure by Letters Patent is:—

1. A reversible taper reamer, comprising a bar having two sets of slots therein at right angles to each other, detachable cutters located in said slots, and locking means for the inner and outer of said cutters, the edges of said inner and outer and intermediate cutters being interlocked with each other.
2. A reversible taper reamer, comprising a bar, having two sets of alining slots therein at right angles to each other, detachable cutters located in said slots, locking means for the inner and outer of said cutters, each of the latter having a central notch in each side thereof, and intermediate cutters having a central notch in only one side thereof, said intermediate and outer cutters being interlocked with each other.
3. In a device of the character stated, a bar having three alining slots therein, and two intermediate alining slots, at right angles to said first mentioned slots, reversible cutters in said slots having their contiguous edges interlocked, and locking devices for the inner and outer cutters.
4. In a device of the character stated, a bar having three alining slots therein, and two intermediate alining slots, at right angles to said first mentioned slots, reversi-
- ble cutters in said slots having their contiguous edges interlocked, the extreme inner and outer of said cutters having a central slot in each edge thereof, a dummy key engaging a slot of said inner cutter, and a set screw engaging a slot of said outer cutter.
5. In a device of the character stated, a bar having two sets of slots therein arranged at angles to each other, detachable cutters in said slots, said cutters having recesses in their juxtaposed edges and being interlocked with each other, and means in the outer end of said bar for locking the outer and other cutters in place.
6. In a device of the character stated, a bar having two sets of slots therein at right angles to each other, detachable cutters located in said slots and having central recesses in their juxtaposed edges, said edges of said inner, outer and intermediate cutters being interlocked with each other, and a set screw extending longitudinally into the outer end of said bar and having its end in engagement with the outer central recess of the outer cutter for locking all of said cutters in position.

MORTON C. HUTCHINSON.
